FRANCIS S. DENNEEN, OF CLEVELAND, OHIO.

METHOD OF MANUFACTURING SHELLS.

1,387,924.

Specification of Letters Patent. Patented Aug. 16, 1921.

Application filed October 4, 1918. Serial No. 256,863.

To all whom it may concern:

Be it known that I, FRANCIS S. DENNEEN, a citizen of the United States of America, and a resident of Cleveland, in the county 5 of Cuyahoga and State of Ohio, have invented a new and useful Method of Manufacturing Shells, which invention is fully set forth in the following specification.

This invention relates to the manufacture 10 of shells or hollow projectiles and, while capable of application to the manufacture of shells for guns of either large or small caliber, has particular utility in the manufacture of shells for guns of the larger cali- 15 bers.

In accordance with the methods now employed in the manufacture of shells to meet the specifications of the U. S. Government, a cast steel billet is rolled into bars to give 20 the steel the proper physical characteristics, and the bar stock is then nicked and broken into blocks of the proper size. The specifications of certain foreign countries however, permit the use of blocks formed by 25 breaking directly from cast steel ingots the top and bottom of the casting so as to leave clear metal; but such cast blocks do not possess the same physical characteristics as rolled stock. The block or slug, whether 30 obtained from bar stock or an ingot, is next heated to a forging temperature and placed in the die of a hydraulic press, which press is provided with one or more piercing tools. The piercing tool or tools are forced into 35 the hot metal to provide a central aperture therein, the metal during the piercing operation flowing upwardly in the die around the piercing tool. While the piercing tool is initially positioned so as to be concentric 40 with the inner surface of the die, the maintenance of this concentric relation during the piercing operation depends almost entirely upon the stiffness of the tool and the homogeneity of the hot metal; consequently, 45 it is a common occurrence for the tool to drift during its entrance into the metal, whereby the aperture formed therein is in eccentric relation with respect to the exterior surface of the blank. Furthermore, the 50 length of shell and the thinness of wall that can be obtained by this piercing operation are limited, both because of the frictional resistance opposing a long draw and because of the cooling of the metal where the wall is 55 thin. Therefore, while it is possible to obtain short, relatively thick-walled shells by this piercing operation, it is practically im-

possible to obtain long, thin-walled shells thereby. Additionally, the flow of the hot metal under the pressure of the piercing 60 tool quickly scores the inner surface of the die, and this effect increases with the length of the draw, so that, as these dies are relatively expensive, the cost of maintenance becomes relatively high. 65

Therefore, if a relatively long, thin shell is to be drawn, the blank, after leaving the piercing press, is subjected to a further drawing operation in a draw-bench, wherein the heated blank is forced by a hydraulic 70 ram through a series of draw-rings which successively decrease in diameter. Such a draw-bench requires the use of a ram having a stroke of several feet and the power consumed in forcing the blank through the 75 successive rings is relatively great. Furthermore, the oxidized scale on the blank quickly scores the operative faces of these rings so that here again the cost of maintenance is relatively high. Additionally, a 80 substantial eccentricity between the exterior and interior surfaces of the blank, which exists in a large percentage of cases, is not corrected by this drawing operation.

While it might be possible theoretically to 85 obtain concentricity between the inner and outer surfaces of the blank from the piercing operation and to maintain this concentricity during the subsequent operations, the resulting increase in the cost of the forging 90 and drawing operations would be so great as to render it impractical. Therefore, it is customary to form the blank from a block having a weight of metal greatly in excess of that of the finished shell so as to allow 95 for machining off the eccentric portion and the irregular portions which result from the drawing operations. With the larger shells this excess of metal is frequently more than one hundred per cent. of the weight 100 of the finished shell. Furthermore, the removal of such excess metal requires a heavy and costly machine equipment and consumes much time and labor. Additionally, if the eccentricity be so great that it would cost 105 more to machine it off than to discard the blank, the forging is thrown into the scrap heap. Therefore, the present method of drawing a shell not only necessitates a large and expensive equipment which consumes 110 a relatively great amount of power and is costly in its upkeep, but it is also highly wasteful of the stock.

It has heretofore been proposed to elimi-

nate the use of draw-benches by passing the blank between longitudinally and transversely movable squeezing dies, by rolling the blank, and by hammering the blank between 5 a stationary die and a movable die, but none of these proposed methods, so far as I am aware, has ever been successful, because none of these methods assures the production of a concentric shell or the correction of eccentricity already existing in a blank in a way 10 that is both practical and economical.

An object of this invention is to provide a method in the manufacture of shells which eliminates the use of a draw-bench; another 15 object of the invention is to provide a method which enables the piercing operation to be kept, as respects length of draw and thickness of wall, within easy working limits so as to decrease the wear on the dies and 20 the loss of stock; another object of the invention is to provide a method which enables the use of a smaller blank, with the consequent consumption of less heat and the employment of a lighter piercing equipment; 25 another object of the invention is to provide a method whereby any eccentricity arising during the piercing operation is corrected so that the blank may be materially reduced in size, the extent of subsequent 30 machining greatly decreased and a substantial saving in stock obtained; another object of the invention is to provide a method which assures a concentric shell so that the blank may be kept closer to final dimensions, 35 whereby less metal need be removed, a lighter machine-tool equipment employed, less power, time and labor consumed, tool wear reduced, and machining to accurate dimensions facilitated; another object of the 40 invention is to provide a method whereby the interior surface of the shell will be left in good condition so that subsequent machining thereof may be reduced or eliminated; another object of the invention is to provide a 45 method whereby eccentric shells heretofore discarded may be reclaimed; another object of the invention is to provide a method whereby a cast ingot may be employed as a blank and the shell still possess the physical 50 characteristics heretofore obtained by the rolling operation. Other objects relate to the provision of a method in the manufacture of shells which is simple, economical and inexpensive to carry out, and which eliminates much of the heavy machine equipment 55 heretofore required.

Stated broadly, the novel method of manufacturing shells comprises: providing a blank having an aperture to receive a mandrel, and hammering said blank, while hot and supported on a mandrel between simultaneously-acting dies the acting faces of which are coaxial with the axis of the mandrel. If the weight or degree of eccentricity 60 of the blank be sufficiently great, the blank

is also preferably provided with a pilot-portion coaxial with the axis of the mandrel aperture to insure that the blank shall start through the dies in concentric relation to its interior surface. Furthermore, if the weight or degree of eccentricity of the blank be sufficiently great, the concentricity between the exterior and interior surfaces may be further assured by mechanically restraining the blank and mandrel from lateral movement during the period that the dies are in engagement therewith. 70

The invention is capable of being carried out in a variety of ways and by the use of a variety of apparatus. One method of procedure is hereinafter described in detail, and one form of apparatus is diagrammatically illustrated on the drawing. It is to be expressly understood, however, that the example taken is for the purposes of illustration only and is not to be construed as a definition of the limits of the invention, reference being had to the appended claims for that purpose. 80

Referring to the drawing,

Figure 1 represents diagrammatically a blank provided with a mandrel-receiving aperture.

Fig. 2 represents diagrammatically a modified form of blank and one which is preferred for the reasons hereafter explained. 95

Fig. 3 represents diagrammatically a blank provided with a beveled pilot-portion coaxial with the axis of the mandrel aperture.

Fig. 4 represents diagrammatically a blank provided with a cylindrical pilot portion coaxial with the axis of the mandrel aperture. 100

Fig. 5 represents diagrammatically a shell after it has been subjected to the hammering action of the simultaneously-acting dies, and 105

Fig. 6 is a schematic view of an apparatus in which the hammering action may be carried out. 110

In the performance of this invention a blank 1 is provided with an aperture 2 to receive a mandrel, such blank having the usual boss 3 for receiving a centering recess to be used in the subsequent machining of the shell. This blank may be a cast steel ingot or it may be a block broken from a bar of rolled stock. The mandrel-receiving aperture may be provided by piercing the ingot or block, as heretofore described or, 115 in case a cast ingot is employed, the aperture may be cast in the same by employing a core. If the aperture be formed by piercing a blank, the wall thereof may be left relatively thick as the thinning of the wall 120 will be obtained by the hammering to which the blank is to be subjected; furthermore, as a smaller blank may be used, a lighter piercing press may be employed, less power is consumed thereby, less heat is required by 125 130

the blank, the labor and discomfort of handling the blank is reduced, the length of draw and loss of stock from eccentricity is decreased, and the scoring of the die is diminished. While the blank may be generally cylindrical, as shown in Fig. 1, the preferred form of blank is one that is tapered to increase in diameter toward its open end as shown at 4 in Fig. 2 so as to provide at the latter point an increased amount of stock which supplies metal for the subsequent drawing operation and therefore reduces the extent of displacement of the metal, and which also retains the heat at that portion of the blank which is last subjected to the hammering action of the dies.

The blank is then heated, or if it has been obtained by piercing a heated block the blank may be sufficiently hot so as not to require reheating, and is placed on a mandrel, after which it is subjected to the hammering action of simultaneously-acting dies. Any suitable apparatus may be employed for this purpose. Referring to Fig. 6 where-
in one form of apparatus is shown schematically, the blank 1 is mounted on a mandrel 5 connected to a shaft 6 which may move longitudinally through the frame 7. To rotate said shaft a pulley 8 is shown keyed thereto and driven by a belt 9. To move the shaft 6 longitudinally a sleeve 10 is shown retained thereon between collars 11 and provided with a rack 12 with which meshes a pinion 13. Said pinion may be driven in any suitable way, either automatically or manually, as by the hand wheel 14. The described apparatus for rotating and advancing the mandrel, however, is to be taken as typical of any suitable means for rotating and advancing the blank with respect to the dies.

In accordance with the present invention, the blank 1 is subjected to the hammering action of simultaneously-acting dies having their acting faces coaxial with the axis of the mandrel upon which the blank is supported, and any suitable apparatus for accomplishing this end may be employed. In the form shown in Fig. 6, 15 represents a pair of heavy dies having their acting faces substantially semi-cylindrical and of a radius to conform with the desired exterior diameter of the finished blank, said dies being suitably beveled at their entrance end 55 as shown at 16 so as to properly guide the blank and draw or swage the metal. These dies are designed to operate as hammers and any suitable means for reciprocating the same in the ways 17 may be provided. In the form shown, said dies are connected by rods 18 to cranks 19 which carry pinions 20 in mesh with gears 21 driven in synchronism by the chain 22 which passes over chain wheels 23 on the stub shafts carrying 60 said gears 21. Any other suitable means,

however, may be employed for operating the dies in synchronism so that the blank shall be subjected to a hammering action of simultaneously-acting dies.

The mandrel and dies may be suitably cooled by water or air-blast and, if found desirable, the blank may be retained on the mandrel against endwise movement in any suitable way, as by a plunger bearing on the end of the blank under spring or fluid pressure and receding before the advance of the mandrel in a manner well understood in the art. Any suitable means or expedient may also be employed to prevent relative rotation between the mandrel and blank. 80

In operation the mandrel is rotated by the pulley 8 and the belt 9, and is fed by the coaction of the pinion 13 and rack 12 longitudinally between the dies 15, the acting faces of which are coaxial with said mandrel. When the dies are in engagement with the blank the belt 9 slips with respect to the pulley 8 so that there is substantially no tendency to twist the fibers of the metal as would be the case if the blank were positively rotated during the period of engagement of the dies therewith. As the blank passes between the dies it is subjected to the hammering action thereof, and said dies, by their hammer blows in succession longitudinally and circumferentially of the blank, draw or swage the same so as to reduce its exterior diameter to a predetermined amount and force the metal longitudinally of the mandrel to elongate and thin the wall of the blank to the desired size. As the axis of the mandrel and therefore the aperture in the blank are coincident with the axis of the active faces of the dies any eccentricity of the blank will be corrected and the finished exterior surface will be concentric with the interior surface. By then withdrawing the mandrel, the finished blank 24 may be stripped therefrom in any suitable way, either automatically or manually. 110

It is sometimes desirable, especially with the larger blanks or if the degree of eccentricity be relatively great, to provide the blank with a pilot-portion to insure that the blank shall start its advance through the dies symmetrically with respect to the axis of the mandrel aperture. Therefore, with the larger sized blanks or where the degree of eccentricity is relatively great, a fact which may be readily determined in any 115 suitable way as the blanks come from the piercing press, the outer end is preferably so shaped as to provide a pilot-portion coaxial with the axis of the mandrel aperture. This pilot-portion may be of any suitable shape, 120 being shown in Fig. 3 as a beveled portion 25, and in Fig. 4 as a cylindrical portion 26, shown as connected by a beveled portion 25 to the body of the blank, and may be formed during the casting of the ingot or by ma- 130

chinning the end of the blank prior to its introduction into the swaging machine.

With the larger sized blanks, or where the degree of eccentricity is great, so that the

- 5 hammer blows of the dies may tend to bend the mandrel and its shaft, it may be desirable to maintain the pilot-portion of the blank in coaxial relation with the axis of the mandrel during the time that the dies are in
- 10 contact with the blank. This end may be accomplished in any suitable way, as by the provision of a ring 27, having an axial opening that will receive the pilot or finished portion of the blank, which travels with the
- 15 blank or permits the same to slip therethrough, such ring preferably being free to rotate with the blank. If means are provided for maintaining the blank against lateral displacement during the engagement of
- 20 the hammer dies 15 therewith, the pilot-portion will preferably be made cylindrical, as shown at 26 in Fig. 4, and may be substantially of the same diameter as the finished blank.
- 25 The hammering to which the blank is subjected, as it is advanced and rotated between the dies 15, changes the physical characteristics of cast metal so as to make it possible to start with a cast ingot and yet obtain a finished blank having substantially as good physical characteristics as if the blank were made from rolled stock. Furthermore, as the blank is hammered into engagement with and drawn along the mandrel, the interior
- 30 surface thereof may be sufficiently smooth so as to require no machining prior to the nosing-in of the shell (except to cut off the locking lug formed by pressing the metal into a groove in the mandrel when such an expedient is employed). It is therefore within the contemplation of this invention to nose in the shell immediately after the swaging operation and without machining the interior surface thereof, whereby only slight reheat-
- 35 ing, if any, of the blank is required.

The method heretofore outlined may also be employed in reclaiming blanks which have been discarded because the eccentricity of the outer surface with respect to the

- 40 inner surface is so great as to render it unprofitable or impossible to machine off the excess metal. In such case, the blank would preferably be provided with a pilot-portion, as heretofore explained, and hammered between the simultaneously-acting dies, while hot and supported on a mandrel, to draw and swage the same concentrically with the aperture and to the proper dimensions. In case the eccentricity renders a portion of the
- 45 wall too thin the blank may be upset so as to thicken the wall prior to the subjection of the blank to the hammering action of the dies.

In case the size or nature of the blank be

- 50 such that the same becomes too cold to com-

plete the drawing in one heat, it is apparent that it can be readily withdrawn from the mandrel and reheated, and the drawing thereupon completed.

It will therefore be perceived that a method of manufacturing shells has been provided which eliminates the use of the draw-bench; which simplifies and cheapens the piercing operation inasmuch as the blank is not drawn into a thin, long wall in the piercing press; which enables the use of a lighter blank and therefore a lighter piercing press with a consequent smaller consumption of power, heat, time and labor; which insures the concentricity of the outer and inner wall at the end of the drawing operation; which enables the use of a smaller blank whereby there is a corresponding reduction of subsequent machining with a corresponding saving in machine equipment, tool wear, and consumption of power, time and labor; which leaves the inner surface of the shell in good condition so that interior machining may be eliminated and the nosing-in operation follow immediately after the draw; which improves the physical characteristics of cast metal so as to enable the use of cast ingots without prior rolling; which eliminates the relatively great waste of stock that has heretofore been unavoidable where the blank had to be progressively drawn and might be eccentric with respect to its inner wall; and which is simple, relatively inexpensive and economical. Furthermore, a process has been provided which not only eliminates the wasting of blanks because of undue eccentricity, but provides for the reclaiming of such blanks as have heretofore been discarded.

While a preferred method embodying the invention has been described with considerable particularity, it is to be expressly understood that the invention is capable of a wide variety of expressions, some of which will readily suggest themselves to those skilled in the art, while certain steps can be used without the employment of other steps. Furthermore, while apparatus for carrying out certain steps of the method has been described, it is to be expressly understood that this apparatus has been selected for purposes of illustration only, as the invention may be practised with a wide variety of apparatus as will be readily appreciated by those skilled in the art. Therefore reference is to be had to the claims hereto appended for a definition of the limits of the invention.

What is claimed is:

1. In the manufacture of shells, providing a blank with an aperture to receive a mandrel, shaping the end of said blank to provide a pilot-portion substantially coaxial with the axis of the mandrel aperture, and

- hammering said blank while hot and supported on a mandrel between opposed simultaneously-acting dies the acting faces of which are coaxial with said mandrel.
5. 2. In the manufacture of shells, providing a blank with a mandrel receiving aperture and an annular wall increasing in thickness toward the apertured end of said blank, shaping the opposite end of said blank to 10 provide a pilot portion substantially coaxial with the axis of the mandrel aperture and hammering the blank while hot and supported on a mandrel between simultaneously-acting dies the acting faces of which are coaxial with said mandrel.
- 15 3. In the manufacture of shells, providing a blank with a mandrel receiving aperture and an annular wall increasing in thickness toward the apertured end of said blank, 20 shaping the opposite end of the blank to provide a pilot portion coaxial with the axis of the mandrel aperture, rotating and advancing said blank while hot and supported on a mandrel between simultaneously-acting dies the acting faces of which are coaxial with the axis of said mandrel, and hammering said blank with said dies to elongate and thin the walls of the same.
- 25 4. The process of reclaiming eccentric shells which comprises rendering the exterior surface of the shell concentric with the interior surface thereof by hammering the shell while hot and supported on a mandrel between simultaneously-acting dies the 30 acting bases of which are coaxial with said mandrel.
- 35 5. In the manufacture of shells, providing a blank with an aperture to receive a mandrel, and elongating and thinning the wall 40 of said blank by hammering the same while hot and supported on a mandrel between synchronously-actuated dies movable toward and from an axis coincident with the axis of said mandrel.
- 45 6. In the manufacture of shells, piercing a blank to provide a mandrel-receiving aperture, and swaging said blank to elongate and thin the wall of the same while rendering the exterior surface thereof concentric with 50 the axis of said aperture by hammering said blank while hot and supported on a mandrel between opposed simultaneously-actuated dies.
- 55 7. In the manufacture of shells, providing a blank with a mandrel-receiving aperture, providing said blank with a beveled pilot-portion substantially symmetrical with the axis of said mandrel-aperture, and hammering said blank while hot and supported on a mandrel between simultaneously-acting dies, the acting faces of which are coaxial with said mandrel.
- 60 8. In the manufacture of shells, providing a blank with a mandrel-receiving aperture, providing said blank with a cylindrical pilot-portion concentric with the axis of said mandrel-aperture, and hammering said blank while hot and supported on a mandrel between simultaneously-acting dies.
- 65 9. The process of reclaiming eccentric shells which comprises shaping the end of said shell to provide a pilot-portion substantially co-axial with the axis of the interior wall of said shell, and hammering said shell while hot and supported on a mandrel between simultaneously-acting dies having the axis of their active faces coincident with the axis of said mandrel.
- 70 10. In the manufacture of shells, providing a blank with an aperture to receive a mandrel, rotating and advancing said blank while hot and supported on a mandrel between simultaneously-actuated dies, and hammering said blank with said dies to elongate and thin the wall of the same.
- 75 11. In the manufacture of shells, providing a blank with an aperture to receive a mandrel, shaping the end of said blank to provide a pilot-portion substantially coaxial with said mandrel aperture, rotating and advancing said blank while hot and supported on a mandrel between synchronously-operating dies having their acting faces coaxial with said mandrel, and hammering said blank with said dies to elongate and thin the 80 wall of the same.
- 80 12. In the manufacture of shells, providing a blank with a mandrel-receiving aperture, supporting said blank on a mandrel, and subjecting said blank while hot to simultaneous hammer blows in succession longitudinally and circumferentially of the same to elongate and thin the wall of said blank.
- 85 13. The process of reclaiming eccentric shells which comprises heating the shell, mounting the heated shell on a mandrel, rotating and advancing said shell and mandrel between simultaneously-acting dies the acting faces of which are co-axial with said mandrel, and hammering said blank with said dies to render its exterior surface concentric with its interior surface while elongating and thinning the same.
- 90 14. In the manufacture of shells, providing a blank with a mandrel-receiving aperture and an annular wall increasing in thickness toward the apertured end of said blank, and elongating and thinning said blank by hammering the same while hot and supported on a mandrel between simultaneously-acting dies having their acting faces coaxial with said mandrel.
- 95 115 15. In testimony whereof I have signed this specification.

FRANCIS S. DENNEEN.
